[57] CLAIM

The ornamental design for a camera unipod or the like, substantially as shown and described.

DESCRIPTION

FIG. 1 is a perspective view of a camera unipod or the like, showing my new design, shown as it appears with the leg partially extended;
FIG. 2 is a front elevational view of the camera unipod shown with the leg retracted;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof.
